4 Claims. (Cl. 214—131)

The present invention relates to a device for fastening working tools on lifting levers of loading trucks, etc.

It is previously known to fasten working tools in the form of loading buckets etc. on the lifting levers of loading trucks by means of down hitches fastened to the upper part of the working tool and hooks at the lower part of the working tool, it being possible to enter a frame articulatedly connected to the lifting levers and fasten it between the hitches and the hooks. The fastening of the working tool to the frame is effected by means of a number of latch pins, which under the action of springs controllable from the driver's seat are pressed towards latch surfaces on the hooks.

It has turned out that such a fastening of the working tool to the frame by means of springs does not provide the necessary fastening, when the device is used with relatively heavy loading trucks.

One of the objects of the invention is therefore to provide a fastening device, which advantageously can be used on band or 4-wheel driven loading trucks.

According to the invention this object is substantially reached as each latch pin is articulatedly connected to a piston rod of a working piston, which is movable in a compression cylinder mounted in the frame and connected to a hydraulic or pneumatic control device preferably located at the driver's seat of the loading truck.

In this way a relatively simple but reliable fastening device is obtained, which also can be used on heavy loading trucks. In comparison with previously known fastening devices of the type mentioned above another advantage is obtained, i.e. even if the working tool is deformed or worn down so that the distances between the hitches and the hooks are considerably increased or reduced, this is compensated by means of the variable piston stroke of the working piston.

Each hook is preferably provided with a notch, in which the free end of the latch pin can be entered and pressed by means of the working piston. The latch pin can preferably be controlled by at least one guide rail etc. It is also suitable that the latch pin is articulatedly connected to a rod, one end of which is articulatedly connected to the frame and the other end of the piston rod. The latch pin may consist of a pin movable in a guide. It is further suitable that the free end of the latch pin co-operating with the hook is wedge-shaped and adapted to engage a hook provided with corresponding notch and latch surface. The working piston is preferably double-acting, and the control device is made as a double piston, which by means of a handle can be pushed in a second compression cylinder, which by tube lines is connected to the first-mentioned compression cylinder.

The invention is further described in the following in connection with accompanying drawings, which schematically and as examples illustrate embodiments of the invention.

FIGURE 1 is a side view showing in section a frame articulatedly fastened to two lifting levers and a working tool fastened thereto in the form of a lifting fork only shown in part, FIGURE 2 is a section of a control device shown on a larger scale for the working piston shown in FIGURE 1 for fastening of the working tool to the frame,

and FIGURE 3 is a side view of another embodiment of the device shown in FIGURE 1.

In FIGURE 1 there is shown a frame 1 known per se, which is fastened to two lifting levers 2, 2 of a loading truck not shown, which frame includes a bracket 3 and a compression cylinder 4 attached thereto, in which a movable double-acting piston 5 with piston rod 6 is adapted. The free end of the piston rod 6 is articulatedly connected to one end of a rod 7, the other end of which is flexibly attached to a bracket 8 fastened to the frame. To the articulated arm 7 a down latch pin 9 is articulatedly connected, which is guided in a guide rail 10 attached to the frame. The compression cylinder 4 is provided with two tube lines 11 and 12, which are connected to a control device 14 located at the driver's seat 13 (FIGURE 2) of the loading truck comprising a double piston articulatedly connected to a handle 15 and designated by 16, 16'.

The working tool shown is a lifting fork 17 which at 20 its upper part is provided with a number of hitches 18 and at its lower part with a number of hooks 19 each having a notch 20 and a latch surface 21, in which notch 20 the free end of the latch pin 9 is intended to engage upon fastening of the fork 17 to the frame of the lifting levers 2, 2. The frame 1 is moreover provided with a horizontal rod 22, which is intended to engage the hitches 18 upon fastening of the working tool to the frame.

When the frame 1 in a way known per se is entered between the hitches 18 and the hooks 19, it bears against 30 the vertical part of the lifting fork 17, after which the handle 15 (FIG. 2) for the control device 14 is turned in the direction B of the arrow. The pressure medium in the tube line 11 then pushes the working piston 5 to the position shown in FIG. 1, where the piston rod puts a down pressure on the latch pin 9, which is brought into the notch 20 and fastens the frame to the lifting fork. When the handle 15 is turned in the direction A of the arrow, the pressure medium in the tube line 12 pushes the piston 5 upwards, the latch pin 9 being drawn out of the notch 20 in the hook 19 and the frame 1 being released from the fork 17.

In FIG. 3 a modified embodiment of the latch pin is shown consisting of a pin 9' running in a guide 10', the free end of which is wedge-shaped and is adapted to engage a hook 19' provided with a corresponding notch 20' and latch surface 21'.

By the invention the advantage is also obtained that no clearance or relative movement between the latch pins 9 and 9' respectively and the hooks 19 and 19' respectively in the fastening position can occur, as the latch pins 9 and 9' respectively, during the work of the loading truck are pressed firmly into the notch 5, 20 and 20', respectively, looseness being avoided and no essential disturbing sound between the latch pins and the hooks and their latch surfaces occurring any longer. As the pushing of the latch hooks 9 and 9' respectively to the notches and the latch surfaces in the respective hooks 19, 19' is hydraulic or pneumatic, all the latch pins will receive the same contact pressure and fastening effect, even if one of 55 the latch pins should be inconsiderably deformed or for other reasons should have another fastening position than the other latch pin or pins.

The embodiments described above and shown on the drawing are of course only to be regarded as non-limiting examples, and their details can be modified in several ways within the scope of the following patent claims. Thus it is possible to use, in loading trucks with hydraulic control of the lifting levers, 2 the hydraulic system that the loading truck already is provided with, the tube lines 11, 12 connected to the cylinder 4 being connected to the hydraulic system of the truck. In this case the safety

valve already existing may be used at possible overload of the device.

I claim:

1. A device for fastening a working tool having at least one down hitch adjacent to the upper end thereof and at least one hook having a notch adjacent to the lower end thereof to the lifting levers of a loading machine comprising a frame articulated to said lifting levers, means on said frame adapted to engage the hitch on said working tool and secure said tool against movement downwardly or laterally relative to said frame, a first cylinder connected at its upper end to said frame, a double acting piston in said first cylinder, a piston rod connected to said piston and extending downwardly beyond the lower end of said first cylinder, means for introducing pressure fluid into the opposite ends of said first cylinder to move said piston upwardly and downwardly, a latching pin connected at its upper end to said piston rod and extending downwardly toward said hook, a guide for said latching pin rigidly secured to said frame, the downward and upward movement of said piston being sufficient to engage and disengage said latching pin with and from said notch respectively.

2. A device as defined in claim 1 comprising an arm articulatedly connected to said frame below said first cylinder, said piston rod and said latching pin being articulatedly connected to said arm.

5 3. A device as defined in claim 1 in which the lower end of said latching pin is wedge shaped.

4. A device as defined in claim 1 comprising means secured to said loading machine for controlling the supply of pressure fluid to said first cylinder, said means comprising a second cylinder, a double piston therein controlling outlets of pressure fluid therefrom to said first cylinder and a handle for moving said double piston in said second cylinder.
